UNITED STATES PATENT OFFICE.

JAMES A. SHIELDS, OF ATLANTA, GEORGIA.

PROCESS OF TREATING SNAP-BOLLS OF COTTON.

1,013,691.

Specification of Letters Patent.

Patented Jan. 2, 1912.

Application filed July 10, 1911. Serial No. 637,794.

To all whom it may concern:

Be it known that I, JAMES A. SHIELDS, a citizen of the United States, residing at Atlanta, in the county of Fulton and State of Georgia, have invented certain new and useful Improvements in Processes for Treating Snap-Bolls of Cotton; and I do hereby declare the following to be a full, clear, and exact description of the invention, such as will enable others skilled in the art to which it appertains to make and use the same.

The present invention relates to a process for treating snap bolls of cotton, and has for its purpose to devise a method for treating the snap bolls in connection with the apparatus set forth in my copending applications, filed March 15, 1910, Serial No. 549,422, and filed May 22, 1911, Serial No. 628,820, to the end that the material may be transferred through the different stages of the operation at such intervals that said material goes through a disintegrating or loosening and cleaning process, thus presenting the same in better condition for treatment than if it were transferred in bulk. As clearly set forth in the above identified application these snap bolls are bolls filled with fully matured cotton but which have not cracked open because of being frost bitten before or just at the time when they were beginning to crack, and to recover the cotton contained in these bolls, which amounts to considerable, is the purpose of the aforesaid and present applications.

Summarily stated the invention proposes to break the bolls by suitable apparatus, then to separate the fiber from the cracked shell, and then to cause the fiber to be loosened or made fluffy through transferring the same by an air column.

With the above mentioned purposes in view the invention consists in the steps and combination of steps disclosed and herein-after particularly claimed, and a suitable apparatus for carrying out the process is shown by the accompanying illustration.

Referring to the construction in detail the apparatus consists in a chute or hopper 1 adapted to receive the bolls in their original condition as they come from the wagon, from which said bolls may be delivered to the chute either by hand, belt elevator or pneumatic conveyer of any appropriate con-

struction. From the chute 1 the bolls are fed into a braker 2 by a toothed roller 3 and a spiked roller 4 shown diagrammatically in the present drawing. From the rollers 3 and 4 the bolls are delivered on to the breaking apparatus proper, and which consists in a belt 5 traveling on pulleys 6 in the direction of the arrow, which belt conveys the bolls to a similar belt 7 traveling on pulleys 8 in the direction of the arrow. The outer pair of pulleys 6 and 8 are disposed in such relation that the material carried by the belt 5 is deposited upon the belt 7, and the inner pair of pulleys are disposed in closer relation than the outer pair to bring the bolls into such position that the bolls are subjected to a crushing action, after which they are fed by a chute 9 into a receiver 10 at the lower end of a pipe or conduit 11.

From the receiver 10 the crushed bolls are conveyed by suction through the pipe 11 and into the pipe 12, where they are delivered to a feeder contained within the casing 13 secured at the lower end of the pipe 12. The suction means for carrying the material consists in a fan 14 drawing 80 through a pipe 15 that communicates with the pipe 12. The crushed bolls are delivered to the feeder in the form of a bat which needs to be broken or disintegrated to prevent the apparatus from clogging, and to effect which said feeder consists in a toothed roller 16 and a spiked roller 17, shown diagrammatically in this illustration, and a larger roller 18 adapted to coact to separate the bat.

The broken bat is next delivered to a separator having a hopper 19 that receives the material from the chute 20 of the feeder. The separator consists of a saw cylinder 21 working through a plurality of ribs 22 that are secured to beams 23, and a spiked cylinder 24. A rotatable cylindrical screen 25 is located directly beneath said spiked cylinder, and is designed to screen or separate from the material the loose particles of dirt, leaves and the like and cause the same to be deposited within a trough 26, whence it is carried off by a spiral conveyer 27. The screen 25 is designed to be rotated slowly and carry therewith the seed cotton which takes the course indicated by the arrows and

comes out beneath the roller 28 or directly under the pipe 29 for a purpose to be presently explained. A small spiked roller 30 coöperates with the saw cylinder 21 to remove the boll husks or pods as they are separated from the seed cotton, and a receptacle 31 is provided to receive said husks as they are removed by the spiked cylinder 30. When a sufficient amount of seed cotton has been deposited beneath the pipe 29 said cotton is conveyed by suction through the pipe 29 and delivered into a pipe 32 and then fed to a gin feeder located within the casing 33. The necessary suction within the pipe 29 for conveying the material as just stated consists in a pipe 34 communicating with the pipe 32 and which branches off from the pipe 15 that leads to the fan 14. An arrangement is provided and will be presently described for causing suction through either of the pipes 11 or 29 while one of said pipes is closed.

The gin feeder in the casing 33 comprises a pair of rollers 35 and 36 and a coöperating larger roller 37 constructed and operating on the same principle as the feeder contained in the casing 13. From the feeder the seed cotton is delivered by a chute 38 into the hopper 39 of a gin 40, which may be either a huller gin or plain gin, and from the gin 40 the ginned cotton is designed to be conveyed to a condenser 41. The cotton seed which is separated by the gin is deposited into a receptacle 42, from where it may be carried off when necessary.

The means for causing suction in either of the pipes 11 and 29, and closing the other, consists in an oscillating valve 43 fulcrumed at 44 in the pipe 15 and having a slotted end member 45. A sprocket wheel 46 carrying a chain 47 is designed to be driven from the shaft of the fan 14. The chain 47 is provided with projecting members 48 disposed at suitable intervals and designed to contact with opposed arms 49 that are loosely journaled on the shaft of the sprocket 46. A stud 50 is secured to one of said arms and moves within the slotted end 45 of the oscillating valve. As the chain 47 travels over the sprocket 46 the projecting members 48 successively engage with the arm 49 projecting to the left and bring said arm around to the position occupied by the arm shown on the right, and in so doing cause the slotted arm of the valve 43 to be moved first to one side and then to the other of the pipe 15, which moves the valve 43 to open and close the pipes 15 and 34 as will be understood.

The receptacles 26 and 42 for the pods and cotton seeds respectively are not absolutely necessary to the carrying out of the operation, as the dirt which would fall in the conveyer receptacle 26 can be dropped through the floor and in like manner the

pods and seeds can be allowed to drop through the floor and then carried away after accumulation.

At the point where the pipe 15 communicates with the pipe 12 there is provided a screen 42^a of fine mesh, the purpose whereof being to prevent the material from entering into the pipe section 15 when the same is entering the pipe 12 from the pipe 11. A valve consisting of two flexible members 43^a 75 is secured within the pipe 12 immediately above the rollers 16 and 17 and has for its purpose to allow of an accumulation of material which will, by the changing of valve 43 from one position to another which cuts off suction and causes flexible valve 43^a to open and cotton to fall upon and on rollers 16 and 17, open said valve and fall upon the rollers 16 and 17; and a further purpose of said valves is to close off suction through 80 the pipe 12 and prevent any material from being carried back through said pipe 12, as will be understood. In like manner the pipe 32 is provided with a fine mesh screen 45^a located to close the opening into the pipe 32 90 and prevent material from being carried through said pipe. A valve 46^a constructed similar to the valve 43^a is mounted in the pipe 32 between the screen 45^a and the crushing rollers 35 and 36 and is adapted to act 95 in a similar capacity as said valve 43.

The process set forth herein is also applicable for treating open as well as snap bolls. Cotton is now picked out by hand from open bolls, while from the method disclosed herein it is necessary only that these bolls after being pulled from the stalks be passed through the machinery and the cotton picked therefrom as it is being ginned, thereby saving much of the expense of picking cotton by the present method.

It is obvious that those skilled in the art may vary from the aforesaid steps in the operation without departing from the spirit of my invention, and I therefore do not wish 110 to be limited to the method set forth except in so far as may be required by the claims.

What I claim is:—

1. The process of treating snap bolls for the recovery of the fiber thereof, consisting 115 in crushing said bolls; transferring the crushed bolls by suction; separating the boll husks from the fiber; transferring the fiber by an air blast to make it fluffy and finally ginning the fiber, substantially as described.

2. The process of treating snap bolls for the recovery of the fiber thereof consisting in crushing said bolls; transferring the crushed bolls by suction for a relatively great distance; separating the boll husks 120 from the fiber and accumulating the fiber in a pile; transferring the pile of fiber by suction for a relatively great distance to render the fiber fluffy, and finally ginning the fluffy fiber, substantially as described. 130

3. The process of treating snap bolls for the recovery of the fiber thereof, consisting in crushing said bolls and forming the same into a bat; transferring said bat by suction 5 for a relatively great distance; breaking up the bat; separating the bat into husks and fiber, and allowing the fiber to accumulate in a pile; transferring the pile of fiber by suction for a relatively great distance where- by to render the fiber fluffy; then breaking 10 the fluffed fiber; and finally ginning the fiber, substantially as described.

In testimony whereof, I affix my signature, in presence of two witnesses.

JAMES A. SHIELDS.
